UNITED STATES PATENT OFFICE.

JOHN A. WILSON, OF MARPLE, NEBRASKA.

PITMAN.

No. 927,392.

Specification of Letters Patent.

Patented July 6, 1909.

Application filed March 14, 1908. Serial No. 421,122.

To all whom it may concern:

Be it known that I, JOHN A. WILSON, a citizen of the United States, residing at Marple, in the county of Boxbutte and State of Nebraska, have invented new and useful Improvements in Pitmen, of which the following is a specification.

This invention relates to pitmen, and the object of the invention is to provide a device 10 of this character which may be readily adjusted to take up wear.

To these ends the invention resides in the novel construction of pitmen, hereinafter fully described and claimed.

15 In the accompanying drawings, Figure 1 is a top plan view of a pitman constructed in accordance with my invention. Fig. 2 is a longitudinal sectional view upon the line 2—2 of Fig. 3. Fig. 3 is a similar view upon 20 the line 3—3 of Fig. 1.

In the accompanying drawings the numeral 1 designates a continuous metal strap, having its ends rounded as indicated in the figures of the drawings. This strap 1 has its 25 sides suitably spaced and its ends provided with reinforcing elements 2. The strap 1 has its sides provided with a plurality of openings adapted for the reception of securing elements, the purpose of which will hereinafter 30 be more fully described. Interposed between the sides of the strap 1 are the pitman sections 3 and 4. These sections 3 and 4 may be constructed of any desired material and are each provided with transverse slots 5, 35 adapted for the reception of retaining bolts 6, which are also adapted for engagement with the openings provided in the sides of the strap 1, and by which the sections 3 and 4 are secured upon the strap. The sections 3 40 and 4 have their ends arc-shaped to complete the circle provided by the ends of the band and the reinforcements 2, whereby a snug bearing is provided for the offsets of the cranks to which the pitman is adapted to be 45 secured. The sections 3 and 4 are also provided with centrally arranged longitudinally extending slots or openings 7, adapted for the reception of retaining elements 8, by which a top plate 9 is secured upon the sec-

tions. This top plate 9 serves as an effective 50 reinforcement for the sections and is provided with a centrally arranged upstanding portion or offset 10. This offset 10 comprises a horizontal wall provided with a suitable centrally arranged opening and outwardly inclined sides connected with the body of the plate. The adjacent ends of the sections 3 and 4 are beveled or inclined toward each other, as indicated by the numerals 11 and 12, and interposed between the faces 11 and 12 is an inclined or beveled spreader element 13. This spreader 13 is provided with a central aperture adapted for the reception of a bolt or other securing device 14, having its threaded portion extending through the opening provided in the horizontal wall of the offset 10 and adapted for the reception of a suitable nut 15, by which the spreader 13 may be drawn toward the horizontal wall of the offset 10 and the arms 55 60 65 70 75

3 and 4 forced toward the ends of the band 1. It will be understood that the retaining elements 6 and 8 have their nuts sufficiently loosened to allow the free movement of the sections 3 and 4.

From the above description it will be seen that I have provided a simple, cheap and effective pitman which may be readily adjusted to compensate for wear by the crank shafts to which the pitman is attached, and 80 one which may be readily adjusted while positioned upon the machine.

Having thus fully described the invention what is claimed as new is:

In a pitman, an endless band of a substantially rectangular formation having its ends rounded, reinforcements for these ends, pitman sections between the sides of the band and extending longitudinally from the center of the band, said sections being each 85 90 95 provided with a series of vertical and transverse elongated openings, securing elements connecting the sides of the band and engaging the transverse openings of the pitman sections, a top plate provided with a central upwardly extending offset portion, headed retaining elements engaging the under face of the pitman sections and extending through

the vertical slots and connected with the top plate, the pitman sections having their meeting ends arranged at angles away from each other, a wedge shaped member for these 5 angular faces, and a threaded element engaging the wedge shaped member and the top of the offset of the top plate, and a threaded securing member engaging the

threaded element, substantially as and for the purpose set forth.

In testimony whereof I affix my signature in presence of two witnesses.

JOHN A. WILSON.
